COMB CLEANER

Ralph M. Brody and Martin H. Brody,
Dorchester, Mass.

Application May 6, 1947, Serial No. 746,388

3 Claims. (Cl. 132—29)

1

The present invention relates to a comb cleaner of the type having numerous substantially parallel strands through which the comb teeth are combed or passed. Such comb cleaners are normally formed of a plurality of strands of threads or strings, held taut in a wire or rigid frame. While such constructions have proven practical and useful, they are apt to be somewhat expensive in construction, difficult to keep clean, and not too sanitary. When strands of threads or cords are held together in a woven piece or clamped at the ends, such end pieces will not only gather dirt as they hang upon the wall, but also in use, so that they must either be washed after practically each use or else soon discarded.

In the present invention, the construction of the comb cleaner is such that it does not tend to gather the dirt on the cleaning strands, and if dirt is gathered it may readily be washed out without causing the cleaner to be wetted to any substantial degree, so that the cleaner will be immediately ready for use.

A further merit of the present invention is that the cleaner is constructed of a single integral piece of material with the cleaning strands having the elasticity of rubber or of the nature of rubber, so that as the strands are stretched their thickness is diminished. The end elements supporting the strands may be of the same thickness as the strands, or they may be thickened in places if desired. By making the cleaner and strands of rubber, synthetic rubber, or the like, as contrasted with woven material of cloth, cotton, wool, etc., the strands will not be wetted and therefore after cleaning will be ready to be used without drying.

By stretching the rubber strands, the thickness will be diminished so that they will fit between most any comb teeth, snugly exerting sufficient friction to thoroughly clean the surfaces at the sides of the teeth. In a comb where teeth are spaced close together, the strands may be stretched until they are thin enough to engage between the comb teeth, after which the tension between the supporting ends may be decreased permitting the strands to engage the sides of the teeth and thoroughly clean them as the comb is drawn through the strands.

The invention will be more fully understood from the description as set forth in the specification, when taken in connection with the drawings illustrating an embodiment of the invention, in which:

Fig. 1 shows a plan view of the comb cleaner; 55

2

Fig. 2 shows a section taken on the section line 2—2 of Fig. 1;

Fig. 3 shows a section taken on the line 3—3 of Fig. 1; and

5 Figs. 4 and 5 show sections of modifications of the arrangement shown in Fig. 1 taken longitudinally of the comb cleaner.

10 Fig. 6 shows a fragmentary plan view of the arrangement of Fig. 4 as viewed in a downward direction.

In the arrangement described in Figs. 1, 2, and 3, the comb cleaner comprises end sections 1 and 2, with center perforations 3 and 4, which may be used for suspending or hanging the comb cleaner.

15 If the comb cleaner is hung at one end, it may be manually stretched by pulling the other end. Between the two ends 1 and 2, which preferably have inner parallel edges such as 5 and 6, there are a plurality of strands 7, 7 extending parallel to one another from the inner edge 5 of section 1 to the inner edge 6 of section 2. These strands and the end pieces 1 and 2 may be of the same material and integral with the end pieces. In fact, the whole comb cleaner 20 may be stamped from a single piece of elastic yielding rubber or rubber-like material, such, for instance, as pure rubber or rubber which might be vulcanized or slightly toughened or hardened. In fact, the end elements 1 and 2 may be more vulcanized or hardened than the connecting strands, 7, 7, which may be permitted to be more yielding and have a greater elasticity, so that they may be more readily stretched with resulting change in thickness.

25 35 In the operation of the device shown in Fig. 1, the perforation 3 of one end may be engaged over a post or hook and the cleaner may be stretched manually by grasping the other end, with a finger inserted in the perforation 4 to aid the grip. The cleaner is then stretched or held taut and the comb is run longitudinally with the teeth engaging the strands, which will rub the wall of the teeth and take out the dirt which might gather between the teeth. Such cleaning may be done 30

40 with water flowing over the comb or the cleaner, and the cleaner may be soaked if desired. After the cleaning has been accomplished, the cleaner may be thoroughly washed, it being sufficiently flexible so that by putting the two end sections 45 together the strands will separate to any width, permitting cleaning of the strands without impairment in any way. Since the cleaner is made of rubber, the water may be just shaken off and it is ready to be used again.

50 55 In the arrangement in Fig. 4, the end portions

8 and 9, corresponding to 1 and 2 of Fig. 1, have thickened or raised sections 10 and 11 extending transversely across the cleaner adjoining the strands 12, so that when the cleaner is stretched between the perforations 13 and 14 the thickened sections 10 and 11 will aid in maintaining the cleaner flat across its width. Another means of accomplishing this result is shown in Fig. 5, where the sections around the perforations 15 and 16, corresponding to the perforations 3 and 4, are thickened so that the end sections 17 and 18, in which the perforations are located, will not buckle but keep flat, thus preserving the strands 19 parallel and level with one another.

The modifications illustrated in Figs. 4 and 5 are used in exactly the same manner as the cleaner in Fig. 1.

Having now described our invention, we claim:

1. A comb cleaner of the type described comprising end elements having parallel joining strands therebetween constructed of flexible, yieldable, stretchable rubber, a thickened section extending transversely across said end elements, located adjacent ends of the strands.

2. A comb cleaner of the type described comprising end elements having parallel joining strands therebetween constructed of flexible, yieldable, stretchable rubber, a thickened section extending transversely across said end elements, located adjacent ends of the strands, said end elements having perforations therethrough located outwardly of said thickened sections.

5
10

3. A comb cleaner of the type described comprising an integral, flexible, yieldable rubber element having end sections with connecting parallel strands extending from the inner edge of one end section to that of the other end section, the end sections and the strands all lying in substantially the same plane, said strands being stretchable to such a thickness that a comb may be run through them for cleaning purposes, said end elements adjacent the strands being substantially thickened in comparison to other parts of the end elements, with perforations provided in the end elements between the thickened sections and the end of each of the end elements.
